UNITED STATES PATENT OFFICE.

GEORGE H. MORGAN, OF UHRICHSVILLE, OHIO.

IMPROVEMENT IN TYPE-WRITING MACHINES.

Specification forming part of Letters Patent No. 173,658, dated February 15, 1876; application filed November 13, 1875.

To all whom it may concern :

Be it known that I, GEORGE H. MORGAN, of Uhrichsville, in the county of Tuscarawas and State of Ohio, have invented certain new and useful Improvements in Type Writing and Printing Machines; and I do hereby declare that the following is a full, clear, and exact description thereof, which will enable others skilled in the art to which it appertains to make and use the same, reference being had to the accompanying drawings, and to the letters of reference marked thereon, which form a part of this specification.

My invention relates to the art of type writing or printing; and consists in a new and improved machine by means of which alphabetical characters are printed with due regard to their difference in size and the space which they occupy—that is, properly spaced, or with proper spaces between the letters, or each of them, and between each word, and with mechanism so arranged that the spaces between the letters may be increased or diminished, as occasion requires; also, in a machine by means of which the different varieties of types, signs, numerals, and other characters used in ordinary printing, may be used without having to set up the type in fixed forms before printing therefrom, the machine printing the required letter or series of letters, or other sign, directly upon the paper from adjustable type carried on a wheel, the blow of the printing-hammer or platen and the movement or adjustment of the paper being effected by one and the same operation, through the instrumentality of mechanism moved by any suitable power, and operated or controlled by finger-keys, all as hereinafter more fully set forth.

In the accompanying drawings, Figure 1 is a top-plan view of my improved type-writing machine. Fig. 2 is a plan view with the paper carrying and operating mechanism removed. Fig. 3 is a vertical sectional view with paper-carrier removed. Fig. 4 is a side elevation of the paper-carrier, and Fig. 5 is a front view of the same. Figs. 6, 7, 8, 9, and 10 are detached views of the sliding rods. Figs. 11 and 12 are detached views of the key or cam rods. Fig. 13 is a detached view of the cam-lever for operating the paper-carrier.

Fig. 14 is a detached view of the cam end of the lever for operating the printing-hammer. Figs. 15 and 16 show operating-rods of modified form.

Referring to the parts by letters, A represents the main shaft of the machine, journaled in suitable bearings on any proper frame or support. B is a cylinder, mounted on or keyed to the shaft A so as to revolve with it, and it may have a band-pulley, b, secured to or formed on it, for the purpose of receiving a band, for operation by power derived from mechanism or other source. C represents a series of longitudinal grooves formed in the cylinder for the reception of a series of rods, D, which may be of the same or different lengths, as found most desirable or convenient. The ends of these rods D project beyond the end of the cylinder opposite to the band-pulley, and are provided with springs d, which hold them in position when not operated on, and stops d⁴ on the cylinder prevent their coming out too far, as hereinafter set forth. The rods D have projections, d¹, on their upper sides, at points corresponding with a series of annular grooves, E, formed in the periphery of the cylinder, into which grooves they project while the rods are at rest, the whole series being arranged on a spiral line around the cylinder.

The inner ends of rods D are made rectangular in their cross-sections, and provided with two rectangular grooves, d² and d³, each having a beveled slide or face at one side, as clearly shown in the drawings—that is to say, the groove d² having at its side an inclined or beveled face, d³, and the groove d³ a correspondingly-inclined face, d⁴. These grooves and beveled faces correspond with two annular grooves, E' E'', formed in the cylinder, the grooves d² and d³ being, respectively, in a line with grooves E' and E'' when the rods are at rest, and the beveled faces d³ and d⁴, respectively, occupying the grooves E' and E'' when the rods are drawn inward in the course of operation. The object of this part of the device will be more fully described hereinafter.

F represents a series of rods or bars, corresponding in number with the grooves E and rods D. These rods F are pivoted at one end between lugs of brackets f, which are held in

position in the frame of the machine by adjusting-screws f^1 , or by other means suitable for adjusting the length of the rods with relation to the cylinder. The free ends of these bars or rods F are hooked or turned down, and their extremities are cut away or formed into triangular cams or keys f^2 , corresponding to the projections d^1 of the rods D, with which they are brought into contact in the operation of the machine. While at rest the hooked or free ends of the rods F remain immediately over, or slightly within, the grooves E, and are kept from contact with the projections d^1 by means of springs f^3 , secured at one end to the frame of the machine. The relative position of the bars F may be further secured by suitable guide plates, with divisions between the bars. G represents a series of finger-keys, corresponding in number with the bars F and rods D, each key representing an alphabetical letter or series of letters, characters, or signs. These keys are provided with stems g, and suitable mechanism for pressing the free ends of the bars F into contact with the projections d^1 on the rods D within the grooves E as the cylinder B revolves, thereby operating to draw the rods D inwardly, as and for the purpose hereinafter set forth. H is the type-wheel, which is keyed to the shaft A, so as to revolve with it and in the same direction as the cylinder B. It may be provided with fixed type h, or with adjustable type-carriers h', either or both; the latter having the same alphabetical letter or character, in different varieties or styles of type, arranged on its periphery, so that a letter in either variety of type may be brought into position for printing, as required.

I do not think it necessary herein to particularly describe the construction and operation of this adjustable type-wheel, as the same forms the subject of Letters Patent granted to me.

As shown in the drawings, the type project from the side of the periphery of the wheel, in position to receive the blow of the printing-hammer, as hereinafter described. I is the inking-roller, mounted upon a shaft, i, secured to the frame of the machine. The ink roller is kept in proper position by means of a rod, i', having a bent or hooked end, which is inserted in a groove, i'', formed in the end of the roller. This rod i' may be adjusted so as to slide the ink-roller back and forth on the shaft i, and the surface of the roller may be provided with different-colored inks at different parts, so as to print with different colors, if desired. No. 1 is a spur-wheel on one end of the shaft A, which gears with a pinion mounted on a shaft secured to the frame of the machine. This pinion gears with another pinion of the same size, and which, in turn, engages with the teeth of a large gear-wheel, 4, mounted on the shaft K. This particular train of gearing is not, however, necessary, as by making the wheels 1 and 4 of sufficient and proper size, and gearing them together,

the required result will be accomplished without the aid of the two pinions; or the gearing may be dispensed with, and bands and pulleys substituted therefor. The shaft K is journaled in proper bearings on the frame of the machine, and carries a pinion, 5, on its inner end. L is a shaft arranged to revolve in proper bearings at right angles to the shaft K. M is a worm gear or screw, keyed to the shaft L on a line with the shaft K, or it may be made to extend some distance along the shaft L. N is a toothed or ratchet wheel, provided with a large number of small teeth, and keyed to the shaft L, so as to revolve with it. O is a spring clamp, the ends of which press against the sides of the wheel N, to keep it in position and insure its turning in the proper direction, and also prevent too free motion. The pawl P is pivoted to a vertically-reciprocating rod, p, which passes through guide-plates p¹, secured to the frame of the machine; and p³ is a spring, one end of which is secured to the rod p, the other pressing against the pawl p, to keep it in position engaged with the ratchet-wheel N. Q is a lever, one end pivoted to the frame, and the other connected with the rod p. q is a rod, one end pivoted to the lever Q, and the other to one end of a horizontal lever, R. This lever R is pivoted centrally to the frame of the machine, and its free end, on the under side, is formed into a cam, r, the form of which is clearly shown in the drawings. This cam r fits into one of the grooves, E', of the cylinder B, and is held in proper working position by a spring, r'. S represents the printing-hammer, one end of its shaft or arm being pivoted to a bracket, s, firmly secured to the frame of the machine, its other or free end being formed into a disk, and provided with a pad of suitable material to soften the blow upon the type. s¹ is another bracket, secured to the frame, its projecting end provided with a pad or cushion, against which the shaft or arm of the hammer strikes when drawn back by the spring. s² is a rod, one end pivoted to the arm of the hammer, and the other connected with one arm of a lever, s³, which is pivoted by means of a bent shaft, s⁴, to brackets or hangers s⁵, secured to the frame of the machine. The other end of the lever s³ is formed into a cam, the peculiar form of which is shown by the drawings.

This cam portion of the lever s³ fits into the other or end groove, E'', of cylinder B, and is operated in manner hereinafter set forth.

When not in use the hammer is kept from contact with the type by means of a spring, s⁶, the end of which bears against the lever s³. 6 and 7 represent two guide-rods, upon which the paper-carrying device is made to slide back and forth. The paper-carrier T is formed of two side pieces or plates, t t, of suitable form, connected together by cross-bars with sufficient rigidity to insure necessary strength and firmness. t¹ is a shaft, journaled in the side plates t t, and provided with two or more

small rollers, t^1 , or wheels of rubber or other suitable elastic material; or, instead of elastic surfaces, the peripheral surface of these rolls may be milled or provided with small teeth to form a slightly roughened surface, and thus insure a regular and positive feed. t^2 t^3 are two springs, the free ends of which bear against the wheels t^1 , the other ends being secured to the side plates t . Springs t^2 t^3 may carry rollers so arranged as to compress the paper between them and the rollers t^1 t^2 , or adjustable or other self-adjusting rollers may be used for the same purpose. t^4 is a ratchet-wheel on the end of shaft t^1 . t^5 is a lever, one end pivoted to one of the plates t , and the other connected by a link or rod, t^4 , to another lever U , which is pivoted to the upper rod 6 . t^6 is a pawl, pivoted to the lever t^5 , its end engaging with the ratchet t^4 , it being held in contact with the ratchet by means of a spring, t^6 . The outer end of lever U is provided with a handle or finger-piece, u , for operation, or the rod 6 itself may be made to turn, and thereby accomplish the same purpose. The other end of this lever is connected with a crank-pin, u^1 , the crank u^2 being secured to the end of a rotary or oscillating rack-bar, V , the ends of which are journaled in the side plates t . The rack-bar V is provided with one or more teeth, v , which may be made to gear with either the spur-wheel 5 or the worm-gear M on shaft L , as desired. W is the roller which carries the paper, and from which it is unrolled, as required in the operation of the machine. It is provided with a series of pins or spurs, w , for securing the end of the paper to the rollers. X is a rod or wire for guiding the paper as it is unrolled. Z is the paper to be printed on by the operation of the machine.

I have shown the machine with the mechanism arranged so that the type-wheel and cylinder revolve in a vertical plane, but it may be arranged so as to have the type-wheel revolve in a horizontal plane, or in an inclined position; or the type-wheel and cylinder may be made to revolve on different shafts and on different planes of motion, as found most desirable or convenient.

I have also shown the keys arranged to operate directly upon the hooked key-rods F , and in position on the top or upper side of the machine; but they may be arranged in a more convenient position, like the key-board of a piano-forte, and connected with the rods by wires, or in any of the well-known ways, unnecessary here to describe.

The operation of the machine is as follows: The necessary motive power being applied, so as to cause the shaft A , cylinder B , and type-wheel H to revolve at the required rate of speed, and the paper to be printed on being in position, we will suppose that the operator desires to print the letter A , or any other particular letter; he presses upon the particular key G , which represents the letter, the hooked end of the corresponding bar F being thereby forced or drawn downward or inward until the

cam f^2 on its end enters and occupies the corresponding annular groove E of the cylinder B . As the latter revolves, the cam f^2 comes in contact with the projection d^1 on the corresponding rod D , said projection d^1 occupying the groove. The cam f^2 will then push or draw the rod D inwardly, within its longitudinal slot C , thereby bringing the beveled faces d^3 and d^4 on the other end of the rod, so as to occupy the annular grooves, E' and E'' . In this position these beveled faces will, respectively, come in contact with the cams on the ends of the levers R and s^3 —the cam on R with d^3 , and the cam on s^3 with d^4 —the former actuating the mechanism for adjusting or moving the paper-carrier transversely from right to left, the latter actuating the printing-hammer, so as to press the paper against the type exposed upon the type-wheel for operation; both operations—that is, the movement of the paper the required distance, and the movement of the printing-hammer so as to press the paper on the type—being accomplished simultaneously through pressure upon a single key. As soon as the cam f^2 is released from the projection d^1 , the spring d on the end of the rod D draws the latter out to its former position, and the pressure being removed from the key G , the spring f^3 raises or withdraws the bar F to its normal position.

The letters of the alphabet being of different sizes, one requiring more space on the paper than another, it is necessary, in order to properly space the printed letters, that the paper should be moved different distances, or distances corresponding to the space required for each letter.

This adjustment or movement of the paper is accomplished by having the beveled faces d^3 on the rods D larger or smaller, as the case may be, so that the cam end of the lever R is moved to a greater or less extent, thereby, through the connecting mechanism, moving the paper from right to left the required distance to suit the different sizes of type.

To make the proper spaces between the words, I use a special key, bar, and reciprocating rod D^1 , differing only from those already described in this, that the beveled face d^8 on the rods D , for operating the printing-hammer, is omitted in the spacing-rod D^1 . By pressing on the spacing-key the paper is moved the required distance without being printed upon.

For increasing the space between the letters, or causing them to be printed wider apart, (which is termed by printers the operation of "justifying,") as is sometimes necessary near the end of a line, I use a special key, bar, and rod, D^2 , in which the beveled face corresponding to d^8 of rod D , for operating the printing-hammer, is omitted, and the beveled face d^9 , which operates the mechanism for moving the paper, is made of small size, so as to move the paper but a short regulated distance. Figs. 6 and 7 show, respectively, a plan and side elevation of one of the rods D , Fig.

8 being a cross-section on the line $x x$, Fig. 6, showing the form of the beveled surface d^3 . Fig. 9 is a side elevation of one end of the spacing-rod with only one beveled surface. Fig. 10 is a similar view of the rod D^2 , used for justifying, as hereinbefore set forth. Figs. 15 and 16, respectively, show rods of modified form, which are operated in a different manner from the rods D —that is, instead of being made to reciprocate within the longitudinal grooves of the cylinder, they are pivoted or journaled, and when operated are made to turn so as to bring the bent portions d^5 into contact with the free ends of the levers R s^3 , for operating the mechanism of the printing-hammer and paper-carrier in substantially the same manner and with the same result accomplished by the beveled faces d^3 and d^8 of rods D , the turning of the rods being accomplished by pressure brought to bear on the projections d^6 , either by the operation of hooked bars, similar to bars F , or by other suitable means.

The operation of the mechanism connected with the printing-hammer will be readily understood by reference to Fig. 3 of the drawings. We have seen that the hammer is actuated by means of the beveled surface d^3 on rods D raising the cam end of lever s^3 . The upper arm of this lever, being connected with the arm of the hammer by the connecting-rod s^2 , will cause the hammer to move outwardly, so as to press the paper against the type, and when the cam end of the lever is released from contact with the rod D , the spring s^6 draws the hammer back or away from the paper.

The hammer moves with great rapidity—that is, the blow is sudden, the time it is in contact with the paper being inappreciable, so that the revolution of the type-wheel does not require to be stopped or arrested in order to receive the blow of the hammer on the type, the printing being accomplished while the wheel is moving at full speed, say two hundred revolutions per minute, and the hammer moves with sufficient rapidity to print all the letters of the alphabet during each revolution of the type-wheel, the different lengths of the rods D , or different positions of the projections d^1 on the rods D , permitting of this movement of the hammer.

The operation of the mechanism for moving the paper-carrier from right to left, and for moving the paper vertically on the carrier, is as follows: We have seen that motion is imparted to this mechanism by means of the rods D moving the cam end of lever R . The other end of the lever being connected with the vertical rod b , a reciprocating movement is thereby imparted to the rod, carrying the pawl P with it. The pawl, engaging with the teeth of ratchet-wheel N , thereby imparts an intermittent rotary motion to the shaft L and worm-gear M , and the latter, gearing with one or other of the teeth v of the bar V , will move the paper-carrier T from right to left

with an intermittent progressive movement, the distance it is moved being regulated, as before described, by the degree of movement given to the cam end of the lever R . In this way the paper is moved the required distance for each letter.

When the carrier has moved completely across, or when the end of the line is reached, or at any other point at which it is desired to reverse the carrier, the operator presses the handle or finger-piece u upward, thereby throwing the teeth v out of gear with the worm-gear M , and into gear with the spur-wheel 5 , the revolution of which carries the paper-carrier back from left to right.

To commence a new line the operator presses the handle u downward, throwing the teeth v again into gear with the worm-gear M . At the same time the downward movement of the handle u causes the pawl t^5 to operate the ratchet-wheel 8 , and thereby turn the shaft t^1 , the rubber wheels on which cause the paper to move upward the distance of one line, or any required distance, as this particular mechanism may be operated while all the other parts of the machine are at rest.

The paper unrolls from the roller W , and is kept taut by the rod and the springs t^2 .

Proper tension is given to the roller by springs or other devices, so as to prevent it unwinding too freely.

Paper prepared for the purpose, and the transfer-ink used by lithographers, may be used with this machine, and the proof, as printed, be transferred to lithographic stones.

What I claim as my invention, and desire to secure by Letters Patent, is—

1. The combination of the cylinder B and cam-bars F with a series of sliding rods, D , provided with two beveled faces, d^3 and d^8 , substantially as and for the purpose set forth.

2. The rods D , cylinder B , and bars F , operating in combination with mechanism, substantially as described, to actuate the printing-hammer, in the manner substantially as and for the purpose set forth.

3. The rods D , cylinder B , and bars F , operating, in combination with mechanism substantially as described, for operating the paper-carrier, substantially as and for the purpose set forth.

4. A rod, D , provided with two cams or laterally-beveled faces, d^3 and d^8 , for the purpose of actuating the levers which operate the paper-carrier and printing-hammer, substantially as specified.

5. A rod, D , constructed with two laterally-beveled faces, d^3 and d^8 , and with a cam-face, d^1 , in the manner substantially as and for the purpose specified.

6. A spacing-rod, D^1 , constructed with a single laterally-beveled face, d^3 , to operate the paper-carrier without actuating the printing-hammer, substantially as and for the purpose specified.

7. The combination of a spacing-rod, D^1 , having a laterally-beveled face, d^3 , and a cam-

face, d^1 , with the cylinder B and cam-bar F, substantially as and for the purpose specified.

8. The combination of the justifying-rod D², constructed with a single laterally-beveled face, d^3 , of diminished size, with the hammer S, actuating-rods D, cylinder B, and cam-bars F, substantially as and for the purpose specified.

9. In a type-writing machine, the combination of a justifying-rod, D², with a spacing-rod, D¹, each being respectively constructed in the manner substantially as and for the purpose specified.

10. The cylinder B and series of rods D, having inclined faces d^3 , of different sizes, proportioned to the different sizes of the letters of the alphabet, characters, or signs, and operating, in combination with a series of cam-bars, F, substantially as and for the purpose specified.

11. The cylinder B, having a series of rods, D, a spacing-rod, D¹, and a justifying-rod, D², in combination with bars F, substantially as and for the purpose specified.

12. The cam-bars F, pivoted to the adjustable brackets f, substantially as and for the purpose specified.

13. The combination of a rod, D, provided with two laterally-beveled faces, d^3 and d^6 , cam-face d^1 , and spring d, with a key, G, cam-bar F, and cylinder B, substantially as and for the purpose set forth.

14. The combination of a series of rods, D, each being provided with two laterally-beveled faces, d^3 and d^6 , cam-face d^1 , and spring d, with a cylinder, B, and a series of keys, G, and cam-bars F, substantially as and for the purpose set forth.

15. In combination with the printing-hammer S, rod s² and cam-lever s³, substantially as and for the purpose specified.

16. The combination of bars F, cylinder B, rods D, cam-lever s³, rod s², and printing-hammer S, substantially as and for the purpose specified.

17. The combination of hammer S, rods s², lever s³, and spring s⁶, substantially as and for the purpose specified.

18. In combination with the paper-carrier T, the worm-gear M, ratchet N, pawl P, rod p, lever Q, rod q, and cam-lever R, substantially as and for the purpose specified.

19. The combination of bars F, cylinder B, rods D, lever R, rod q, lever Q, rod p, pawl P, ratchet N, and worm-gear M, substantially as and for the purpose specified.

20. In a type writing or printing machine, the combination of the following instrumentalities, to wit: a printing-hammer, S, and paper-carrier T, operated simultaneously by

pressure on a single finger-key by means of a bar, F, cylinder B, rod D, and connecting mechanism, substantially as described.

21. In a type writing or printing machine, the combination of the following instrumentalities, to wit: a printing-hammer, S, paper-carrier T, and revolving type-wheel H, having adjustable type-carriers, each operated in the manner and for the purpose substantially as set forth.

22. In a type writing or printing machine, the combination of the following instrumentalities, to wit: a revolving type-wheel having independent adjustable type-carriers and printing-hammer, operated substantially as and for the purpose specified.

23. In a type writing or printing machine, the combination of the following instrumentalities, to wit: a revolving type-wheel having independent adjustable type-carriers, printing-hammer, and paper-carrier, operated substantially as and for the purpose specified.

24. The combination of a revolving type-wheel, H, printing-hammer S, cylinder B, sliding rods D, and cam-bars F, substantially as and for the purpose specified.

25. The combination of a revolving type-wheel, H, printing-hammer S, paper-carrier T, cylinder B, sliding rods D, and cam-bars F, substantially as and for the purpose specified.

26. The ratchet-wheel N, operating substantially as described, in combination with the worm-gear M, adjustable rack-bar V, and paper-carrier, substantially as and for the purpose specified.

27. The combination of a paper-carrier with an adjustable rack-bar, V, lever U, and crank u, substantially as and for the purpose specified.

28. The combination of the lever U, rack-bar V, and spur-wheel 5, substantially as and for the purpose specified.

29. The combination of the lever U, rack-bar V, and worm-gear M, substantially as and for the purpose specified.

30. The combination of the levers U and t³, ratchet 8, and pawl t⁵, and shaft t¹ and rollers, substantially as and for the purpose specified.

31. The shaft t¹, with elastic wheels, in combination with springs t² and roller W, substantially as and for the purpose specified.

In testimony that I claim the foregoing as my own I affix my signature in presence of two witnesses.

GEORGE H. MORGAN.
